UNITED STATES PATENT OFFICE

155,873

DESIGN FOR A CHAIN FOR A BRACELET OR SIMILAR ARTICLE

Michael Chernow, New York, N. Y.

Application February 11, 1948, Serial No. 144,413

Term of patent 14 years

(Cl. D45—16)

To all whom it may concern:

Be it known that I, Michael Chernow, a citizen of the United States and residing at New York, in the county of New York and State of New York, have invented a new, original, and ornamental Design for a Chain for a Bracelet or Similar Article, of which the following is a specification, reference being had to the accompanying drawings, forming part thereof, and in which

Fig. 1 is a top plan view of a chain for a bracelet, showing my new design,

Fig. 2 is a side elevational view thereof, and

Fig. 3 is an end elevational view of one of the links.

The dominant feature of my design resides in the links shown in full lines, which links are repeated throughout the length of the chain as indicated by the broken lines illustration.

I claim:

The ornamental design for a chain for a bracelet or similar article, substantially as shown and described.

MICHAEL CHERNOW.
